LAWN SPRINKLER BASE

Frederick David Chapman, Chicago, Ill., assignor to Scovill Manufacturing Company, Waterbury, Conn., a corporation of Connecticut

Application May 13, 1957, Serial No. 46,139

Term of patent 7 years

(Cl. D91—1)

Fig. 1

Fig. 2

Fig. 3

Fig. 5

Fig. 4

Fig. 1 is a perspective view of a lawn sprinkler base embodying my new design.

Fig. 2 is a reduced top plan view thereof.

Fig. 3 is a front elevation thereof.

Fig. 4 is a side elevation thereof; and

Fig. 5 is a rear elevation thereof with one of the legs fragmentarily shown for convenience of illustration.

I claim:

The ornamental design for a lawn sprinkler base, substantially as shown.
